CLAIM

The ornamental design for a blender as shown and described.

DESCRIPTION

FIG. 1 is a top perspective view of a blender according to the claimed design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom perspective view thereof.

The portions of the article shown in broken line form no part of the claimed design, with broken lines adjacent shaded areas representing the bounds of the claimed design.

1 Claim, 8 Drawing Sheets
